UNITED STATES PATENT OFFICE.

JEREMIAH J. SULLIVAN, OF NASHVILLE, TENNESSEE.

ARCH BRICK.

Application filed December 1, 1922. Serial No. 604,120.

To all whom it may concern:

Be it known that I, JEREMIAH J. SULLIVAN, a citizen of the United States, and residing at Nashville, in the county of Davidson and State of Tennessee, have invented a new and useful Improvement in Arch Bricks, of which the following specification is a full disclosure.

This invention relates generally to improvements in partition or arch walls especially applicable to locomotive boiler furnaces, and particularly to the form of brick employed in forming the wall and to the method of sustaining the brick.

It is a general practice in the construction of arch walls for locomotive boiler furnaces to form the walls of bricks disposed in rows, between and resting upon a plurality of longitudinally arranged and definitely spaced parallel inclined water circulating tubes, the bricks of each row being transverse to the tubes, and at their opposite ends grooved to engage about the tubes, between which they lie to prevent longitudinal movement of the bricks. The bricks of one row have a square edge or plane end abutment with the adjacent ends of the bricks of the second row and therefore only a limited or no transverse movement is permitted with respect to the tubes. Should the bricks warp or buckle under the action of the heat they either distort the tubes or injure or crack the bricks.

It is therefore an object of the invention to rest the bricks tangentially upon the tubes, allowing the bricks to slide transversely upon the tubes, and secondly, to overlappingly endwise engage the bricks of one row with those of an adjacent row with the overlapping ends of the bricks of a form to permit a hingelike action of the bricks one upon the other to avoid fracture of the bricks.

An object of the invention is therefore to provide a partition wall or arch formed of bricks which can be hingedly fitted together in the various combinations required by the different fire box constructions, to form a continuous solid partition, or arch, the wall being supported in such manner as to be expandable without injury to the arch, arch supports, or sides of the fire box.

Other objects and certain advantages will be more fully described in the description of

the drawings forming a part of this application, in which drawings:

Figure 1 is a vertical longitudinal section showing a portion of a locomotive fire box having an arch or division wall constructed and mounted in accordance with this invention.

Figure 2 is a fragmentary top plan view corresponding to Fig. 1.

Figure 3 is a cross sectional view through the fire box and arch wall, showing a construction wherein two arch tubes support the arch.

Figure 4 is a view similar to Fig. 3, showing a construction wherein three arch tubes support the arch.

Figure 5 is a similar view showing a four arch tube construction.

Figures 6 and 7 are respectively an edge view and a bottom plan of the key or wedge brick, constructed in accordance with this invention.

Figures 8 and 9 are respectively an edge view and a bottom plan of a body or intermediate brick having relatively parallel slanting ogee-shaped surfaces on two opposite parallel edges.

Figures 10 and 11 are respectively an edge view and a bottom plan of an intermediate brick having convergently related upwardly facing ogee-shaped surfaces at two opposite parallel sides.

Figures 12 and 13 are respectively an edge view and a bottom plan of another form of intermediate brick having relatively opposite related downwardly convergent ogee-shaped surfaces.

Referring to Figure 1, which represents a portion of a locomotive boiler furnace, the numeral 1 designates the fire box of any preferred construction which is divided into upper and lower communicating chambers by a refractory arch or partition wall constructed in accordance with the present invention. The fire box as herein shown is composed of a door sheet 2, side sheets 3, crown sheet 4, and tube sheet 5, only a portion of the tube sheet being shown and the tubes omitted. The arch tubes 6 connect the water spaces at relatively opposite sides of the fire box in the usual manner, and form supports for the arch composed of my improved refractory end overlapping bricks of two classes, designed herein as intermediate

or body bricks and key or wedge bricks. Any number of tubes may be used, Figures 2, 4, and 5 illustrating arch constructions supported respectively by two, three and 5 four arch tubes. The intermediate bricks rest upon the supports or tubes in tangential relation thereto, and as shown in Fig. 3, the intermediate or body bricks 10 rest tangentially upon and bridge the two arch tubes 6 and are held thereon from lateral displacement by wedge or key bricks 11 engaged with the opposite sides of the intermediate bricks at one end and at their opposite ends with the side sheets 3 of the furnace. The 10 bricks 11 are angularly disposed with relation to the intermediate bricks and are inclined upwardly therefrom, to permit the arch, under the influence of fluctuating temperatures, to expand, the bricks 11 sliding 15 along the inner surfaces of the furnace side walls or sheets to permit of such expansion, without deformation of the side walls. The bricks 10 are of similar configuration and detailed description will therefore be directed 20 to the structure of a single brick. An edge view and a top plan of one form of body or intermediate brick are shown respectively in Figures 10 and 11.

The brick 10 is of rectangular configuration and has a pair of oppositely related shorter parallel edges cut as at 12 to provide surfaces of ogee-configuration or ogee-ends, the surfaces being relatively convergent toward the face side of the brick. This permits the bricks to be overlappingly engaged but free to rock or swing one upon another. The brick has a socket 13 formed in its lower face for the purpose of reducing weight, and thickness, preventing fracture 25 of the brick due to expansion and contraction of the same and providing gas mixing pockets. The wedge or key brick 11, an edge view and elevation of which are respectively shown in Figs. 1 and 2, is of rectangular configuration and has an upper plane face 15, is rounded at one end, as at 16, for engagement with the upper part of the ogee-shaped surface of an intermediate brick, and has its lower plane face 17 convergently related to the face 15. The outer or wall-engaging end of the brick at its thinner edge is rounded and curved in planes at right angles to each other, as at 18, for engagement with the side sheets 3, and 30 when the bricks are positioned to form the arch wall, circulating spaces *a* are provided between the side sheet and bricks, extending from center to center of adjacent bricks, as shown in Figure 2. The rounded end 16 of the brick 11 is complementary to the upper portion of the ogee-shaped surface of an intermediate brick, said ends being adapted to have a socket fit thereagainst, as shown in Figures 3, 4 and 5.

25 Another form of intermediate or body

brick 25 is shown in Figures 12 and 13, which are respectively an edge view and a bottom plan of the brick in which the ogee-shaped surfaces are downwardly convergent and downwardly faced, as at 20, the bottom 70 of the brick being grooved as at 21.

In Figures 8 and 9 are shown respectively an edge view and plan of a fourth form 75 of body brick 22, having the ogee-shaped surfaces 23 parallel and in angular relation to the parallel plane faces of the brick and complementary to the angular disposition of the surfaces of the other forms of bricks.

All bricks may be manipulated, reversed, and fitted together in various combinations, 80 conformably to requirements, as shown in Figures 3, 4, and 5.

With the plane lower surfaces of the bricks resting upon the tubes in tangential relation thereto, the wall as a whole is free 85 to expand and contract, side sheet deformation being avoided, inasmuch as the key or wedge bricks, during wall expansion or contraction, slide upwardly or downwardly against said sheets 3. The relatively reversed relation of the ogee-shaped surfaces at the ends of the body or intermediate bricks 10 and 25, and the relative parallel 90 ogee formation of the bricks 22, provides for the fitting together of the bricks in the 95 various combinations required for arches, supported respectively by two or more arch tubes. The curved end formation 18 of the bricks 11 provides sufficient space between the bricks and the side sheets 3, for circulation 100 of heated air at those points.

Having described my invention, I claim:

1. In a fire box having arch tubes longitudinally arranged therein, a refractory arch comprising a plurality of bricks tangentially supported and slideable upon said tubes, said arch composed of body bricks having at two opposite edges opposingly related parallel surfaces of ogee configuration adapting the bricks to be adjacently complementally overlappingly nested within the edge dimensions of the bricks and non-interlockingly engaged, and key bricks disposed at opposite sides of said body bricks, said key bricks having rounded ends 110 fitted against corresponding outer surfaces of said body bricks.

2. In a fire box having arch tubes longitudinally arranged therein, a refractory arch comprising a plurality of bricks bridging and resting upon said tubes in tangential relation thereto each brick having two opposite parallel edges of ogee configuration, the ogee shaped surfaces of all bricks complementary, enabling the bricks to be overlappingly nested and non-interlockingly engaged together in varying combinations, and key bricks disposed at opposite sides of said first-mentioned bricks, said key bricks having complementary surfaces 125 130

fitted against the corresponding surfaces of said first-mentioned bricks, the opposite ends of said key bricks engaging the side walls of said fire box in angular relation thereto.

3. In combination with a fire box having longitudinally disposed parallel arch tubes therein, and a refractory arch supported upon said tubes, said arch formed of fire bricks slidably disposed upon said tubes in tangential relation thereto, each brick having opposite end surfaces of ogee configuration, adapting the bricks to be adjacently complementally overlappingly nested within the edge dimensions of the bricks and non-interlockingly engaged, and key bricks having rounded opposite ends of relatively different radius, the end of largest radius engaged with a portion of the ogee surfaces of said first-mentioned bricks and the opposite ends in engagement with the side sheets of said fire box.

4. In combination with a fire box, a fire arch, comprising tubes having a refractory arch supported thereon, said arch composed of intermediate bricks, bridging and resting upon said tubes in tangential relation thereto, said bricks having formed on their opposite parallel sides, surfaces of ogee configuration, said bricks mutually hinged- 25
30
35
ly fitted together by overlapping corresponding ogee-shaped surfaces, and tapering key bricks having one end engaged with the upper portion of the outer ogee surfaces of the first-mentioned bricks, the opposite ends supported by the side sheets of said fire box.

In witness whereof, I hereunto subscribe my name, as attested by the two subscribing witnesses.

JEREMIAH J. SULLIVAN.
